Primary Examiner — Ian Simmons*Assistant Examiner* — Charles Hanson(74) *Attorney, Agent, or Firm* — Ostrolenk Faber LLP(57) **CLAIM**

The ornamental design for a bottle trumpet, as shown and described.

DESCRIPTION

FIG. 1 is a perspective view of a bottle trumpet showing my new design;

FIG. 2 is a view of any side thereof; and,

FIG. 3 is a top view thereof.

The elements of a bottle trumpet shown in broken lines form no part of the claimed design.
